(57) **CLAIM**

We claim the ornamental design for the roll over protection structure, as shown and described.

DESCRIPTION

FIG. 1 is a rear right side perspective view of a roll over protection structure;

FIG. 2 is a right side view thereof;

FIG. 3 is a left side view thereof;

FIG. 4 is a top view thereof;

FIG. 5 is a front view thereof;

FIG. 6 is a rear view thereof; and,

FIG. 7 is a rear perspective view of the roll over protection structure mounted to an excavator.

The broken lines are for illustrative purposes only and form no part of the claimed design.
